PRESSURE CASTING APPARATUS

Filed Sept. 16, 1920

Inventor -
Silvio Brusa
By - B. Amiger, Atty.

UNITED STATES PATENT OFFICE.

SILVIO BRUSA, OF MILAN, ITALY.

PRESSURE-CASTING APPARATUS.

Application filed September 16, 1920. Serial No. 410,636.

To all whom it may concern:

Be it known that I, SILVIO BRUSA, a subject of the King of Italy, and a resident of Milan, Italy, have invented certain new and 5 useful Improvements in Pressure-Casting Apparatus, for which I filed an application in Italy, June 7, 1919, of which the following is a specification.

The present invention relates to a new or 10 improved means for running off metals into a mould or into a shell. According to the invention the metal is not run off by tilting the crucible or melting pot, but by removing the liquid metal from the crucible to the 15 mould or to the shell, by means of gas, oil, or other fluid under pressure.

To more fully comprehend the invention, reference is directed to the accompanying drawing, wherein the figure shows one construction of apparatus for carrying the invention into effect.

In the crucible or melting pot 1, and consequently in the liquid metal contained therein, is immersed until it rests on the bottom a bent pipe 2 of refractory material. Another pipe 3 connects one of the ends of the pipe 2 to a vessel 4 containing air, gas, or other suitable fluid under pressure, the fluid varying according to the metal employed.

The other end of the pipe 2 is formed with a conical seating 5 into which can be inserted the conical end 6 of a pipe 7 slideable in the hole 8 provided in the support 9. The pipe 7 is maintained in raised position by a counterweight 10 provided on the end of a lever 11 pivoted at 12. Under these conditions the liquid metal fills the bent pipe 2.

When it is desired to run off the metal, 40 the parts 13, 13' of the shell or mould mounted on the blocks 14, 14' of the levers 15, 15' are brought together, these levers being connected by a hinge 16 embracing the pivot 17.

This having been accomplished the inclined plane 18 is caused to slide on the upper part of the pipe 7 until the lever 15' rests against the abutment 20. In this position the bore of the pipe 7 registers with the mouth of the shell. If then the cock 22 inserted in the pipe 3 is opened, the air or other fluid under pressure will pass into the pipe 2 and force the liquid metal into the shell through the bore 21 of the pipe 7.

The metal thus discharged rapidly fills all 55 the interstices of the shell or mould and thus a perfect casting is obtained.

What I claim is:

A crucible or the like; a pipe having a discharge end arranged in the crucible for 60 immersion in molten metal, means to force gas and hence also molten metal through said pipe, a support, a pipe mounted for vertical movement in the support and arranged, when lowered, to close its lower end in the 65 discharge opening of the first-named pipe, a mold, a carrier element for the mold, including a cam to depress the second named pipe and cause the mouth of the mold to register with said pipe when the carrier element is 70 moved in one direction, and means to raise said pipe and thereby disconnect the same from the first-named pipe, when the carrier element moves the mold out of registry with the second named pipe.

In witness whereof I affix my signature.

SILVIO BRUSA.
